UNITED STATES PATENT OFFICE.

DANIEL E. KEMPSTER, OF BOSTON, MASS., ASSIGNOR TO GEORGE W. SMITH,
OF SAME PLACE, AND BENJAMIN F. SMITH, OF SOMERVILLE, MASS.

HAND DRILLING-MACHINE.

SPECIFICATION forming part of Letters Patent No. 289,110, dated November 27, 1883.

Application filed November 13, 1882. (No model.)

To all whom it may concern:

Be it known that I, DANIEL E. KEMPSTER, a citizen of the United States, residing at Boston, in the county of Suffolk and State of Massachusetts, have invented certain new and useful Improvements in Hand Drilling-Machines; and I do hereby declare that the same are fully described in the following specification and illustrated in the accompanying drawings.

My invention relates to that class of hand drilling-machines commonly called "ratchet-drills," in which intermittent rotary motion is imparted to the drill-socket spindle by means of the intermittent action of a frictional locking device, which locks the drill-spindle and oscillating part together in one direction and disengages it in the opposite direction.

The object of my improvements is to provide a more simple and efficient locking device, and to produce a hand drilling-machine which will be more useful, noiseless, and durable, and can be manufactured at less expense; and it consists in the construction herein described and shown.

Figure 1 is a side elevation of my improved hand drilling-machine. Fig. 2 is a sectional view of the same. Fig. 3 is a cross-section on the line $x-x$, seen from V in Fig. 2. Fig. 4 is a longitudinal section of the frictional locking-roll. Fig. 5 is a sectional view of a modification of my improvements. Fig. 6 is a cross-section of the same on the line $y-y$, seen from U in Fig. 5.

Similar letters of reference indicate like parts wherever they occur in all the figures.

A is the drill-spindle, having the drill-socket a and the screw-center a' , and provided with cams $a'' a''$. B is the circular flange, having lever-socket b and lever b' ; C, the frictional locking-rolls. d is the spiral spring, and e the forked spindles for the same. The spindle A has holes e' , for the ends of the forked spindles e to enter, thus holding them in position. The spindle A is cored through its center from end to end, thus giving a chance to file out true the socket a , the end opposite being cored smaller to allow for tapping out for the screw-center a' , the screw being made long enough to reach the tapering end of the drill-shank.

and force it out of the socket a when required so to do. The construction of the different parts is with a view to using steel or other castings, and is designed, especially, to get the greatest amount of strength with the least amount of weight, and more especially to dispense with labor in making the various parts. Therefore I prefer to make the circular flange B with a strengthening-rib, b'' , and the inside of the flange I form tapering in from opposite sides, smaller at the center, as shown in Fig. 2. This gives a good draft to the pattern, and the castings come clean and smooth, requiring no finishing. It is obvious that one or more cams a'' may be formed on the spindle A, and the operation will be the same. I prefer to use two cams $a'' a''$, one on each side of the spindle, as shown in Fig. 3. By so doing I am enabled, in a two-part flask, to cast the spindles complete, with holes e' , requiring no drilling or finishing of the cams. The cams $a'' a''$, as shown in Figs. 2 and 3, are formed tapering, larger in the center, to coincide with the circular flange B, surrounding them. The spindle A has an enlarged portion or collar, the part a''' of the said collar being finished or turned concentric with the spindle A. A finished ring, a'''' , is fitted to revolve freely on the part a''' of the spindle A. Dowel-pins $b''' b'''$ connect the ring a'''' and the flange B concentrically together. Thus it will be seen that the unfinished working parts of the flange B and spindle A do not touch each other, but are held concentric with each other by the dowels $b''' b'''$ and the ring a'''' , revolving on the part a'' , as shown in Fig. 2. The rolls C are tapered toward the center about the same shape as the space or recess c between the flange B and the cams a'' , and are placed one in each space, as shown in Fig. 3. The center of the roll C is reduced to form a journal, c' , which is partly surrounded, when in position, by the forked end of the spindle e , the opposite end of which enters the holes e' in the spindle A. Spiral springs d surround the spindles e . One end of the said springs presses against the spindle A and the opposite end presses against shoulders on the forked spindles. This causes the rolls C to be forced into the smaller part of the space c . A collar, f , held to the spin-

dle A by a set-screw, f' , comes up to and in contact with the flange B, covering up the working parts and protecting them from dirt, as well as securely holding the several parts together in position. The lever b' is held in the socket b by a set-screw, f'' , and may be quickly removed when required, as is often the case when drilling a hole in a space too small to admit the working of the lever b' ; also, in drilling large holes it is often desirable to extend the lever to an unusual length. An adjustable lever is therefore a very great advantage; yet it may be made all in one piece, if so preferred, as heretofore.

15 Figs. 5 and 6 show one modification of my improved drill. It is essentially the same as the other, only the cams $a'' a''$ are on the inside of a flange which is a part of the spindle A. The lever-flange B extends into the cammed 20 spindle and forms a space c , in which are straight rolls C, having a journal c' , and pressed up by forked spindles $e e$, operated by springs $d d$, as before described.

The operation must be obvious to all that 25 when the lever b' is moved in one direction the frictional contact of the circular flange B and spindle-cams $a'' a''$ will grasp or wedge the locking-rolls C and securely lock the parts together, and thus rotate the drill. When the 30 motion of the lever b' is reversed, the grip between the flange B and spindle A is released and the drill remains stationary. Now, owing to the springs d pressing the locking-rolls C so closely into the narrowing part of the space or 35 recess c , the locking together of the parts will instantly take place on reversing the motion of the lever b' , thus effectually preventing any lost motion. Of course, a continuous rotary motion of the drill would take place if the 40 cams $a'' a''$ were double, and two circular flanges

with two levers b' were used alternately, and this construction will form a subject for application for patent for treadle motion hereafter.

I also use this device in a bow drilling-machine. The lever b' and socket b are dispensed with, and two flanges B are used in the form of grooved pulleys, around which the bow-cords are passed in opposite directions, thus producing a continuous rotary motion of the drill 45 in one direction. This will also form a subject for future application for a patent.

I have shown and described my invention in the preferred form, though of course it will be evident to those skilled in the art that 55 the several parts of the same are susceptible of modifications without departing from the spirit of my invention.

The advantages of this contrivance in points of simplicity, effectiveness, and cheapness are 60 too obvious to require comment.

I claim—

1. The locking-roll C, having central journal, c' , substantially as and for the purpose set forth.

2. The locking-roll C, tapering from opposite ends, smaller in the center, the flange B, tapering from opposite sides on its inner surface to the center, and the spindle-cams a'' , tapering from opposite sides, larger in the center, so that when all are together their contacting surfaces coincide with each other, as 70 described and set forth.

In testimony whereof I have affixed my signature in presence of two witnesses.

DANIEL E. KEMPSTER.
